UNITED STATES PATENT OFFICE.

DANIEL J. O'DONNELL, OF CLEVELAND, OHIO.

COMBINATION LOCK.

Application filed July 29, 1920. Serial No. 399,721.

To all whom it may concern:

Be it known that I, DANIEL J. O'DONNELL, a citizen of the United States, resident of Cleveland, county of Cuyahoga, and 5 State of Ohio, have invented new and useful Improvements in Combination Locks, of which the following is a specification, the principle of the invention being herein explained and the best mode in which I have 10 contemplated applying that principle, so as to distinguish it from other inventions.

My invention relates to locks, and particularly to combination door locks.

The annexed drawings and the following 15 description set forth in detail certain means embodying my invention, the disclosed means, however, constituting but one of the various mechanical forms in which the principle of the invention may be employed.

20 In said annexed drawings:

Figure 1 represents a vertical cross section through a door in which my improved lock is positioned, showing elements co-operating both with an outside knob and an 25 inside knob, and also elements, hereinafter fully described, adapted for use in rendering the locking parts temporarily ineffective;

Figure 2 represents a fragmentary elevation of the inside of the lock, showing a 30 retaining tongue and actuating parts;

Figure 3 represents an outside elevation of the lock, a cover for a ratchet being indicated by dotted lines, this view being taken from the plane indicated by lines III—III, 35 Figure 1;

Figure 4 represents a fragmentary elevation, taken from the plane indicated by the line IV—IV, Figure 1;

Figure 5 represents fragmentary elevation, taken from the plane indicated by the line V—V, Figure 1;

Figure 6 represents a horizontal section, taken in the plane indicated by the line VI—VI, Figure 5;

45 Figure 7 is an inside view, showing an elevation of certain cam mechanism for working the combination, in the starting position;

Figure 8 is a sectional elevation taken 50 from the plane indicated by the line VIII—VIII, Figure 7;

Figure 9 is a fragmentary view of the elements shown in Figure 7, after the combination has been partially worked and, in 55 dotted lines showing the position of an operating finger, hereinafter fully described,

after the combination has been worked to a slight extent beyond that shown in full lines in said figure, thus completing, in the form of device illustrated, the working of one 60 number of the combination;

Figure 10 is a sectional elevation, taken from the plane indicated by the line X—X, Figure 9;

Figure 11 is a view similar to Figure 9, 65 showing the position of certain elements after the combination has been worked to a station beyond that shown in Figure 9, and, in dotted lines, to a station still further advanced, completing the working of the sec- 70 ond number;

Figure 12 is a sectional elevation, taken from the plane indicated by the line XII—XII, Figure 11;

Figure 13 represents the elements of Fig- 75 ure 11 at a later stage, and, in dotted lines, to a still later stage, completing the work- ing of the combination, the afore-mentioned operating finger, consisting of a bent wire element, having been rotated at this stage 80 through a total of substantially ninety (90) degrees, from the starting position shown in Figure 7;

Figure 14 represents a sectional elevation, taken from the plane indicated by the line 85 XIV—XIV, Figure 13;

Figure 15 represents the elements shown in Figures 7, 9, 11 and 13 at a stage where the aforementioned operating finger is about to be turned through an additional 90 angle of ninety (90) degrees;

Figure 16 represents a view of the same 95 elements when the operating finger has lifted a certain latch, hereinafter fully de- scribed;

Figure 17 represents a view of the same elements at the time that a certain action, induced by a beveled surface upon the latch and causing a slight forward movement of an outer spindle, is about to take place; 100

Figures 18 and 19 represent elevations, respectively, taken from planes angularly related ninety (90) degrees apart, of said tumbler;

Figure 20 represents a fragmentary, 105 central section through the inner end of the outside spindle, taken in the plane indicated by the line XX—XX, Figure 7;

Figure 21 represents a horizontal section, taken in the planes indicated by the lines 110 XXI—XXI, Figure 16; and

Figure 22 represents a fragmentary sec-

tion, taken in the plane indicated by the line XXII—XXII, Figure 17.

Referring to the annexed drawings, in which the same ordinals respectively refer to the same elements in the several views, there are indicated by the ordinals 1 and 2, Figure 1, casing members secured together by pins 3 and adapted to form a housing for my improved lock, and also adapted to be positioned in the door frame 46. Upon an inside spindle 5 is secured an operating knob 4, and upon an outside spindle 7 is secured an operating knob 6. Secured to the inside face of the casing element 1 is a plate 28 having an annular outer end member 28' within which is journaled a hollow casting 29 having a rectangular hole 29' therethrough, adapted to receive the inner ends of the spindles 5 and 7. This casting 29 is also journaled in the casing member 1 and has diametrically opposed ears 30, one of which, the upper one, Figure 2, lies contiguously adjacent the casing member 1, and the lower of which is somewhat spaced from said casing member. Slidably mounted in the casing member 1 on the pin 33 is a tongue-bolt 35 having a locking tongue 36 and formed at its inner end into a yoke-shaped member with its two arms 31 lying respectively substantially in the same vertical planes as the two ears 30 of the casting 29, as plainly shown in Figure 1, the ends 32 of the two arms 31 being respectively bent inwardly and outwardly over the ears 30 so as to contact with the inner faces of said ears. A spring 34 is disposed in the bolt 35 between the tongue 36 and the pin 33 and the stress of such spring is such as normally to hold the tongue 36 in its extreme outer position. It is evident that the rotation of the casting 29 in the bearings formed by the casing member 1 and the member 28' will cause one or the other of the ears 30 to move the bolt 35 longitudinally and move the tongue 36 inwardly against the action of the spring 34 so as to pull the tongue 36 from the door frame. This part of my mechanism is of standard construction, in so far as the locking tongue elements are concerned, and is adapted to be utilized in connection with the inside knob 4 which, it is contemplated, will always be free to open the door, without the necessity of first working the combination. In order that this inside mechanism may be retained within the door frame 6, I secure to the inside face of the frame by means of the screws 43' a plate 43, Figures 1 and 4, through which an enlarged portion 42 of the spindle 5 passes, there being secured to the inner face of said plate 43, by means of screws 44', a second plate 44 having a yoke shaped lower end 44' adapted to seat closely within a contracted portion 5' of the spindle 5, and between the enlarged portions 42, Figure 1, the yoke portion 44' extending

somewhat below the spindle portions 42, as plainly shown in Figure 1. It is evident that the construction just described will prevent the inward or outward movement through the casing 46 of the spindle 5.

Referring now to the outside spindle 7, which is adapted to be operated by the knob 6, it is intended that the same should actuate the casting 29 and thus the tongue bolt 35, whenever said spindle 7 can be forced into the rectangular hole 29' formed in said casting, and that normally it should be held out of the rectangular hole 29' in said casing, i. e., in the position shown in Figure 1. Furthermore, it is contemplated that one or any desirable number of combinations, dependent upon the position, lengths, etc., of different elements, hereinafter fully described, should be worked by means of turning the knob 6, before the spindle 7 can be forced into or will automatically seek the opening 29'. This combination consists of a certain construction of cam mechanism which will now be described. Briefly, this combination mechanism consists of a latch which is adapted to keep the spindle 7 from being pushed inwardly or pulled outwardly; a tumbler secured to the spindle 7 and adapted, in certain positions and pursuant to certain actuations, to lift the latch to free the spindle; and certain elements determining and causing the action of the operating finger whereby the latter is put in position as it rotates with the spindle, which is capable of turning, to lift the latch to free the spindle. The aforementioned latch is indicated by the ordinal 9, and the same is pivotally mounted on the plate 2 at one end by means of a pin 10 and held to said plate at its other end, in so far as any forward movement or any outward movement from the plate is concerned, by means of a screw 12 under the head of which said outer end of the latch 9 is adapted to move adjacently the casing member 2. This latch 9 is formed with an undercut 9' adapted to fit over and closely adjacent to a reduced portion 8, Figure 21, of the spindle 7. By means of a spring 11 secured to the inner end of the latch 9 and also secured to a screw 11' in the plate 2, the latch 9 is normally held down tightly to the spindle portion 8. Interiorly of the portion 8 the spindle 7 is formed with a flange 24 and exteriorly of the spindle portion 8, the spindle 7 is formed with an exteriorly beveled shoulder 7', Figures 1 and 20. Rotatably secured within the flange 24 is an operating finger 18 whose detailed construction is plainly shown in Figures 18 and 19. This operating finger is a wire having bent ends 19 and 20, the end 20 being bent at an angle of about forty-five degrees from the angularity of the end 19. For purposes, which will herein-after fully be understood, the end 19 is a thin or sharpened portion and the end 20 is thick-

ened or blunt. Furthermore, centrally of its ends and also substantially centrally of the flange 24, the operating finger 18 is formed with a thin body portion 18' having 5 a flat face. This construction is substantially that created by cutting away for the desired distance, substantially half of the material of which the substantially cylindrical body portion 18 is comprised. This is 10 also plainly illustrated in Figure 18.

Referring to Figure 20, it will be noted that intermediately the inner end 7' of the spindle 7 and a floating plate 22 disposed within said spindle and adjacently the flattened central portion 18' of the finger 18, is a spring 23. It is evident that, inasmuch as the finger 18 is free to turn in the flange 24, the operating finger will be automatically turned back into the position shown in Figure 20, if it is turned manually substantially less than ninety (90) degrees, because the plate 22 bears against the flattened portion 18' of the finger 18, being pressed thereagainst by reason of the tension of the spring 23, and the unequal pressure upon the tumbler, at any angle substantially less than ninety (90) degrees, will turn the finger into the position shown in Figure 20. When the finger 18 is in a position ninety or more 30 degrees or, of course, a multiple of ninety (90) degrees, from that shown in Figure 20, the pressure of the plate 22 is distributed evenly over the surface of the finger 18, against which it presses, and induces no 35 turning of the finger 18 in either direction.

Assuming the elements to be those hereinbefore described and their actions such as indicated, it is evident that in certain positions the angular ends 19 and 20 of the finger 18 could be made to act upon the latch 9 as the finger is rotated, and in other positions would be free to turn with the spindle 7 without contacting the latch 9. The construction is such that these results take place. 40 Now, when the finger 18 turns freely with the spindle 7 so as to have no effect upon the latch 9, it is evident that the door cannot be opened. Furthermore, it is also evident, that if the finger 18 lifts the latch 9 to free 45 the spindle 7 so that the latter can be moved inwardly, the door can be opened. Certain elements now to be described form a combination which when worked, in any one of many possible combinations, react upon the finger 18 to cause the same to be turned 50 ninety degrees or a multiple thereof, which, in turn, puts the finger 18 into position to lift the latch 9. Unless the whole combination is worked, and unless each element 55 thereof is worked properly, the finger 18 will be freed from the restraint imposed upon it, before it is turned ninety degrees and, under the action of the spring 23 and the floating plate 22, will automatically 60 turn to a position where it cannot contact

with the latch 9 to lift the same. These combination elements consist of certain wires 25, 26, 27 and 45, Figures 7 to 17, of which the wires 25, 26 and 27 act to turn the finger 18 through ninety degrees and the wire 45 70 acts to turn the same through a further ninety degrees, that is, into a position 180 degrees from that shown in Figures 7 and 20 so that the finger can lift the latch 9. The wires 25, 26 and 27 are spring elements 75 secured at one end to the inside face of the casing member 2 and may, if desired, be assisted in tending to keep their normal positions by means of springs, such as illustrated by 26'. Also, pieces of rubber, such as 25' and 27', may be secured to their free ends for the purpose of deadening the noise caused by the working of the combination. The wire 45 is a short, substantially unyieldable element also secured to casing member 80 2. In working the combination, the tensions of the wires 25, 26 and 27 act upon the sharpened end 19 of the finger 18 to turn the latter, as it rotates with the spindle 7, through ninety degrees, dotted lines, Figure 13, and 85 then the wire 45 acts upon the sharpened end 19 to turn the finger through a further ninety degrees, Figure 16, when the blunt end 20 is then in such position as to be able, upon the turning of the spindle 7, to lift the 90 latch 9. The various steps of effecting the 95 aforescribed result are shown in Figures 7 to 17. The starting position of the combination mechanism is shown in Figure 7. This is a starting position which 100 can be obtained by any desirable means, such as positioning the knob 6 in a certain position which it is known will cause the combination mechanism to be at the proper starting position, inasmuch as the 105 spindle 7 rotates with the knob 6 and the finger 18 rotates with the spindle 7. In the combination illustrated in the accompanying drawings, and here described, for purposes of illustration, the spindle 7 is turned so as to 110 bring the finger 18 into the position shown in Figure 9. This action would be caused by a movement of the knob 6 from right to left. It is evident from Figure 10 that the sharpened end 19 of the finger 18 now extends between the wires 25 and 26, and the pressure and position of such wires are such that the finger 18, in travelling from the position 115 shown in Figure 7 to that shown in full lines, Figure 9, has been turned through a 120 fraction of 90 degrees. This is only a portion of the first length of travel of the finger 18 or the working of the first number of the combination, the full length of travel being indicated by the dotted line position of 125 the finger 18 in Figure 9. In this position, in the combination chosen for illustration, the sharpened end 19 of the finger 18 has been freed from the wire 26, and the wire 25 is 130 pressing against it and preventing it from

turning into its normal position, i. e., that shown in Figures 7 and 20. The tension and position of this wire is such that although the finger 18 tends automatically to turn back into the position shown in Figure 7, due to the unbalanced position of the plate 22, still it is restrained from so doing by said wire 25. The next step is to turn the finger 18 to the left, Figure 9, into a position shown in dotted lines in Figure 11, a position immediately short of said position being indicated in full lines in said figure. During this action, the end 19 of the finger first rides upon the wire 25, and then rides upon the wire 26, being continuously turned on its axis so that, when it reaches the position shown in dotted lines in Figure 11, it rests upon the wire 27, being restrained by both of the wires 26 and 27, and has been turned through the greater part of ninety (90) degrees from the position shown in Figure 7. In the form of combination shown, the next step is to turn the finger 18 to the right from the position shown in Figure 11 to that shown in Figure 13, where, in dotted lines, is shown the completion of this stage of the working of the combination, and in full lines is shown a stage immediately short of the complete stage. By the time the sharpened end 19 of the finger 18 has reached the position shown in dotted lines in Figure 13, the finger has been turned through a complete ninety degree angle and does not tend to return to the position shown in Figure 7, for the reasons hereinbefore explained, and as will be fully understood from the aforesaid explanation, in combination with a study of the elements as shown in Figure 20. The spindle 7 is then turned to the left, Figures 13 and 15, until the sharpened end 19 strikes the inwardly turned end 45' of the rigid wire 45, Figure 15, which, upon the continued turning of the spindle 7 turns the finger 18 through another ninety degrees into the position shown in Figures 16 and 17. This turning of the finger through 180 degrees, from the position shown in Figure 7 to that shown in Figure 17, has resulted in the turning of the blunt end 20 from a position where it extends inwardly from the flange 24 to a position where it extends outwardly so as to come beneath the latch 9, when the spindle has been turned to bring the finger 18 in the position shown in Figure 16. The continued turning of the spindle 7 by means of the knob 6 will cause the blunt end 20 of the finger 18 to lift the latch 9, as plainly shown in Figure 16, so that the spindle is freed from said latch 9. The beveled or inclined surface 9² upon the latch 9 raises the latch 9 and forces the spindle inwardly, the inward action of the spindle, of course, being primarily accomplished by means of deliberately forcing the same in by means of the knob 6 concurrently with the

lifting of the latch 9 by means of the finger 18. This inward movement of the spindle 7 forces the same into the rectangular hole 29' of the casting 29 when the tongue 36 can be actuated and released from the door frame to open the door. A continued turning of the knob 6 will cause the end 20 of the finger 18 to drag upon the surface 9² of the latch 9 and be turned so as to bring the operating finger into the position shown in Figure 7, when, by pulling the knob outwardly the latch 9 will drop down into position over the portion 8 of the spindle 7 to lock the door, the flange 24 passing the latch 9 by reason of the outwardly beveled surface 7³ upon said flange 24. Also, a turning of the knob 6 from left to right will trip the operating finger and lock the door, unless the operating finger is in the position shown in dotted lines in Figure 13, in which case, as soon as the end 20 of the finger gets to the position shown in Figure 16, the latch 9 would again be raised. In this event, a turning of the knob 6 from right to left will trip the tumbler 18 and lock the door.

If desired, as explained above, the wire members 25, 26 and 27 may be in part controlled by springs such as 26', Figures 7, 11 and 13. Furthermore, I have shown formed upon the enlarged spindle portion 7⁴ a ratchet 13, Figures 1 and 3, over which plays a pawl 14 having teeth 14' held to engagement with the ratchet 13 by means of a spring 15 secured to a wire 14² in turn secured to said pawl 14, the other end of the spring being secured to a screw 2' fastened in the plate 2. The outer end of the pawl 14 is of yoke shaped formation 14³ with an outer open end and is pivoted adjacent this opening and intermediate the arms of the yoke, upon a screw 16 secured in the plate 2. The purpose of the ratchet is simply to enable the operator, by means of the clicking thereof, to follow the action of the tumbler and wires by ear, in order more definitely to sense the operation of the lock. If desired, a cover 17 may be provided for the ratchet elements, as plainly shown in dotted lines in Figure 3. If it is desired to retain the spindle 7 in an unlocked position, I use certain elements plainly shown in Figures 1, 5 and 6, and the same consist of a plate 37 secured to the door casing 46, the spindle 7 passing through said plate. To the outer face of the plate 37 is secured a sliding plate 38 having a yoke shaped end 38' adapted snugly to encircle a portion 7² of the spindle 7 smaller than the adjacent portions 7⁴. The plate 38 slides within the plate 37, as plainly shown in Figures 5 and 6, and is held to its lowermost possible position by means of a spring 39 contained within a chamber 38² in said plate 38, and intermediately an outwardly extending shoulder 37' of the plate 37 and the floor of the plate 38, Figures 1 and 5.

It is evident that if the spindle 7 is forced inwardly so that the yoke 38' can drop and encircle the reduced portion 7² of the spindle 7, the latter will be fixed in its innermost 5 position and the door can be left unlocked.

By means of a knob or hand-piece 40 secured in the plate 38, the latter can be lifted to release the spindle 7 from the yoke 38', so that it is possible to pull the spindle 7 out-

wardly and lock the door.

I have shown and described only one combination, but the same can be varied, as desired, by using different numbers of wires; having the wires of different lengths; having 15 different correct starting positions for the knob when commencing to work the combination, etc.

What I claim is:

1. In a combination lock, a bolt formed 20 with a tongue; actuating means for said bolt, said means being comprised of a plurality of interlocking sections; means normally holding said sections in a non-cooperating condition; means adapted to actuate said holding 25 means to cause the latter to release said sections, whereby the latter can cooperate, said last-named means including an operating finger mounted in the inner end of said spindle and cam mechanism adapted by the 30 working of a combination to actuate said finger; and a manually operable handle for working the combination, said handle being secured to one of the sections of said bolt-actuating means.

35 2. In a combination lock, a bolt formed with a tongue; actuating means for said bolt, said means comprising a rotatable casting formed with a slot rectangular in cross-section, and a spindle which is reciprocable 40 and has a portion adapted to interlock with said slot; means normally holding said casting and spindle in a non-cooperating condition; means adapted to actuate said holding means to cause the latter to release said reciprocable spindle, said last-named means including an operating finger fitted through the inner end of said spindle and cam mechanism adapted by the working of a combination to actuate said finger; and a 45 manually operable handle for working the combination, said handle being secured to said reciprocable spindle.

50 3. In a combination lock, a bolt formed with a tongue; actuating means for said bolt, said means comprising a rotatable casting formed with a slot rectangular in cross-section, and a spindle which is reciprocable and has a portion adapted to interlock with said slot; a latch adapted to hold said reciprocable spindle so that normally it cannot be moved into engagement with said slot; means adapted to actuate said latch to release said spindle, said last-named means including an operating finger mounted within 55 the inner end of said spindle and cam

mechanism adapted by the working of a combination to actuate said finger; and a manually operable handle for working the combination, said handle being secured to said reciprocable spindle.

70 4. In a combination lock, a bolt formed with a tongue; actuating means for said bolt, said means comprising a rotatable casting formed with a slot rectangular in cross-section, and a spindle which is reciprocable and has a portion adapted to interlock with said slot; a latch adapted to hold said reciprocable spindle so that normally it cannot be moved into engagement with said slot; means adapted to actuate said latch to release said spindle, said last-named means including a rotatable operating finger fitted through the inner end of said spindle and cam mechanism disposed in the paths of movement of said finger and adapted by the 80 working of a combination to cause the latter to actuate said latch; and a manually operable handle for working the combination, said handle being secured to said reciprocable spindle.

85 5. In a combination lock, a bolt formed with a tongue; actuating means for said bolt, said means comprising a rotatable casting formed with a slot rectangular in cross-section, and a spindle which is reciprocable and has a portion adapted to interlock with said slot; a latch adapted to hold said reciprocable spindle so that normally it cannot be moved into engagement with said slot; means adapted to actuate said latch to release said spindle, said last-named means including a rotatable operating finger mounted in said reciprocable spindle and cam mechanism disposed in the paths of movement of said finger, said cam mechanism 90 comprising a plurality of overlapping elements lying in different planes and adapted during a plurality of definite successive movements of said finger to turn the latter through a definite angle, whereby the finger can actuate the latch to release the spindle; and a manually operable handle for working the combination, said handle being secured to said reciprocable spindle.

100 6. In a combination lock, a bolt formed with a tongue; actuating means for said bolt, said means comprising a rotatable casting formed with a slot rectangular in cross-section, and a spindle which is reciprocable and has a portion adapted to interlock with said slot; a latch adapted to hold said reciprocable spindle so that normally it cannot be moved into engagement with said slot; means adapted to actuate said latch to release said spindle; said last-named means including a rotatable 105 operating finger mounted in said reciprocable spindle and cam mechanism disposed in the paths of movement of said finger, said cam mechanism comprising a plurality of overlapping elements lying in different planes.

planes and adapted, during a plurality of definite successive movements of said finger to turn the latter through a definite angle, whereby the finger can actuate the latch to 5 release the spindle; means tending to turn said finger back into its starting position during the successive movements of the same; and a manually operable handle for working the combination, said handle being 10 secured to said reciprocable spindle.

7. In a combination lock, a bolt formed with a tongue; actuating means for said bolt, said means comprising a rotatable casting formed with a slot rectangular in cross-section, and a spindle which is reciprocable and has a portion adapted to interlock with 15 said slot; a latch adapted to hold said reciprocable spindle so that normally it cannot be moved into engagement with said slot; means adapted to actuate said latch to release said spindle, said last-named means including a rotatable operating finger mounted in said reciprocable spindle and cam mechanism disposed in the paths of 20 movement of said finger, said cam mechanism comprising a plurality of overlapping elements lying in different planes and adapted, during a plurality of definite successive movements of said finger to turn the latter through a definite angle of ninety (90) degrees; means adapted, upon the further movement of said finger, to turn the latter through another ninety (90) degrees, whereby the finger can then actuate the latch to release the 25 spindle; and a manually operable handle for working the combination, said handle being secured to said reciprocable spindle.

8. In a combination lock, a bolt formed with a tongue; actuating means for said bolt, 40 said means comprising a rotatable casting formed with a slot rectangular in cross-section, and a spindle which is reciprocable and has a portion adapted to interlock with said slot; a latch adapted to hold said reciprocable spindle so that normally it cannot be moved into engagement with said slot; means adapted to actuate said latch to release said spindle, said last-named means including a rotatable operating finger mounted in said 45 reciprocable spindle and cam mechanism disposed in the paths of movement of said finger, said cam mechanism comprising a plurality of overlapping elements lying in different planes and adapted, during a plurality of definite successive movements of said finger to turn the latter through a definite angle, whereby the finger can actuate the latch to release the spindle; means adapted to turn the finger back to its starting position, if it is turned too far; and a manually operable handle for working the combination, said handle being secured to said reciprocable spindle.

65 9. In a combination lock, a bolt formed

with a tongue; actuating means for said bolt, said means comprising a rotatable casting formed with a slot rectangular in cross-section, and a spindle which is reciprocable and has a portion adapted to interlock with 70 said slot; a latch adapted to hold said reciprocable spindle so that normally it cannot be moved into engagement with said slot; means adapted to actuate said latch to release said spindle, said last-named means including a rotatable operating finger mounted in said reciprocable bolt and cam mechanism disposed in the paths of movement of said finger, said cam mechanism comprising a plurality of relatively vertically disposed resilient wires having overlapping ends and adapted, during a plurality of definite successive movements of said finger to turn the latter through a definite angle, whereby the finger can actuate the latch to release the spindle; and a manually operable handle for working the combination, said handle being secured to said reciprocable spindle. 75

10. In a combination lock, a bolt formed with a tongue; actuating means for said bolt, said means comprising a rotatable casting formed with a slot rectangular in cross-section, and a spindle which is reciprocable and has a portion adapted to interlock with 90 said slot; a latch adapted to hold said reciprocable spindle so that normally it cannot be moved into engagement with said slot; means adapted to actuate said latch to release said spindle, said last-named means including a rotatable operating finger mounted in said reciprocable bolt, and cam mechanism disposed in the paths of movement of said finger, said cam mechanism comprising a plurality of overlapping elements lying in different planes and adapted, during a plurality of definite successive movements of said finger to turn the latter through a definite angle, whereby the finger can actuate the latch to release the spindle; means adapted to turn the finger back to its starting position, if it is turned too far; and a manually operable handle for working the combination, said handle being secured to said reciprocable spindle. 95

11. In a combination lock, a bolt formed with a tongue; actuating means for said bolt, said means comprising a rotatable casting formed with a slot rectangular in cross-section, and a spindle which is reciprocable 100 and has a portion adapted to interlock with said slot; a latch adapted to hold said reciprocable spindle so that normally it cannot be moved into engagement with said slot; means adapted to actuate said latch to release said spindle, said last-named means including a rotatable operating finger mounted in said reciprocable spindle and cam mechanism disposed in the paths of movement of said finger, said cam mechanism 105

comprising a plurality of overlapping elements lying in different planes and adapted, during a plurality of definite successive movements of said finger to turn the latter 5 through an angle of ninety (90) degrees; a rigid wire element adapted, upon the further movement of said finger, to turn the latter through another ninety (90) degrees, whereby the finger can then actuate the latch 10 to release the bolt; and a manually operable handle for working the combination, said

handle being secured to said reciprocable spindle.

12. In a combination lock, a bolt; a reciprocable spindle; an operating finger rotatably mounted therein having a plane face; a floating plate disposed adjacent said finger face, and means resiliently holding said plate against said finger face. 15

Signed by me this 15th day of July, 1920. 20

DANIEL J. O'DONNELL.
